UNITED STATES PATENT OFFICE.

GEORGE C. SEYMOUR, OF NEW YORK, N. Y.

HEEL.

1,320,417.

Specification of Letters Patent.

Patented Nov. 4, 1919.

Application filed January 21, 1919. Serial No. 272,324.

To all whom it may concern:

Be it known that I, GEORGE C. SEYMOUR, a citizen of the United States, and a resident of the city of New York, borough of Brooklyn, in the county of Kings and State of New York, have invented a new and Improved Heel, of which the following is a full, clear, and exact description.

This invention relates to an improved heel 10 and has for an object the provision of an improved construction whereby certain parts of the heel are easily removed whereby other parts may be substituted whenever desired.

Another object in view is to provide a 15 heel with what may be termed a frame, a cushioning section, and a removable locking section.

A further object in view is to provide a heel arranged with a rubber or other cushioning section which is removable and a locking section therefor utilizing the resiliency of the rubber as a locking spring, the construction being such that the bottom of the heel is inclined toward the bottom of the 25 shoe more especially in the back when in use, thereby increasing the height of the heel at the point of greatest impact, and affording a longer wearing action to the resilient member.

30 A still further object of the invention is to provide a heel with a clamping section and a resilient section, said sections being so constructed that both sections may be removed without the use of tools and a new 35 section substituted.

In the accompanying drawing:

Figure 1 is a side view of a shoe with the heel embodying the invention shown applied thereto.

40 Fig. 2 is a bottom plan view of the rear part of the shoe shown in Fig. 1 disclosing the arrangement of resilient section in regard to the remaining part of the heel.

45 Fig. 3 is a view similar to Fig. 2, but showing the parts as they appear with the clamping section removed.

Fig. 4 is a section through Fig. 2 on line 4—4.

50 Fig. 5 is a view similar to Fig. 4, but showing the clamping section about to be removed.

Fig. 6 is a bottom plan view of the clamping section removed.

55 Fig. 7 is a bottom plan view of the resilient section embodying certain features of the invention.

Referring to the accompanying drawing

by numerals, 1 indicates an ordinary shoe which is provided with a specially constructed heel 2 secured in any suitable manner, as for instance by screws 3. This heel, as shown more particularly in Figs. 2 to 7 comprises a base or frame 4, a locking section 5 and a resilient section 6. The section 5 conforms to the shape of an ordinary heel 60 except the rear part which is provided with an arc-shaped cutaway portion 7 for receiving the resilient section 6. Resilient section 6 is preferably made from a good quality of rubber and constructed so that the 65 two edges 8 and 8' are on the same arc so that the section may be arranged as shown in Figs. 2 and 3, or may be reversed when the edge 8 is worn away. The inner part of the resilient section 6 is cutaway at 9 so 70 as to provide resilient retaining members 10 and 11, said retaining members being formed with flanges 12 and 13 for fitting into the groove 14 formed in the rear part of the base 4 and into the groove 15 formed in the 75 rear part of the clamping or locking member 5. The groove 15 is formed by a flange or extending bead 16 projecting from the main body of the clamping or locking section 5. Preferably the cutaway portion 9 does not 80 extend for the full length of the section 6 and consequently the ends of the section 6 may, if desired, be provided with flanges 17 and 18 merging into flanges 12 and 13 so as to fit beneath the overhanging flange or projection 19 of base 4. This overhanging projection extends from point 20 to point 21 and not only accommodates the ends and one side of the resilient section 16, but also accommodates the underlying projections 22 85 and 23 formed on section 5. In forming the projections 22 and 23 grooves or sockets 24 and 25 are produced for receiving the flange 19 adjacent points 20 and 21. The flanges 22 and 23 act as retaining means for 90 holding the rear part of the locking section 5 in place and consequently assists in locking the resilient section 6 in place. The forward part of section 5 is provided with a groove 26 and an overhanging flange 27 100 adapted to fit into the groove 28 arranged beneath the flange 29 on base 4. These interlocking flanges are used to lock the section 5 at the forward end against accidental disengagement. When it is desired to assemble the sections 5 and 6 with base 4 section 6 is first slid into position from the opening 30 and then the section 5 is positioned substantially as shown in Fig. 5; a 105 110

continued movement of the section 5 toward the shoe 1 will cause the flange 27 to snap into the groove 28, the forward movement of the section 5 being caused by the resilient action of the entire section 6 and particularly the resilient action of the members 10 and 11. If desired the lower faces of the sections 5 and 6 may be parallel and in the same plane as the bottom of the sole of the shoe 1, though preferably the lower face of these two members, especially the resilient section are arranged at an angle, which in effect cause the entire heel to be somewhat wedge shape. This construction is provided in order to cause the rear or heel portion of the shoe to be somewhat elevated and thereby depress the toe end of the shoe while at the same time allowing the bottom of the heel structure to engage flatwise against the ground when in use.

Whenever the rubber cushioning member 6 is worn to an undesirable extent section 5 may be removed after which section 6 may be reversed and the locking section 5 returned to its former position, so that the opposite edge of section 6 will be the wearing edge. When this second edge has been worn away and it is desired to supply a new resilient section the locking section 5 is removed by forcing the same rearwardly until the flange 27 can pass flange 29 and then the section 5 swung as if on a pivot until the flange 27 has passed flange 29 whereupon the section may be easily removed and also the resilient section 6. After the new section has been provided the locking section is returned as heretofore described and the heel is then in substantially the condition as when new, as the section 5 is not subject to great wear. If some of the rear part of section 5 wears it will not injure the section nor in any way prevent the parts from acting as described. The entire heel may be made from any desired material without departing from the spirit of the invention, except that the section 6 is preferably of some good quality rubber, or a mixture of rubber and some other material. A desirable material for section 5 is hard rubber or hard rubber with a leather outside or bottom face. The base 4 may also be made of any desired material, as for instance hard rubber. It will be observed that after the heel has been placed in position on the shoe the section 6 may be renewed from time to time without the use of tools, and if desired the locking section 5 may be renewed though ordinarily this is not necessary.

60 What I claim is:

1. A heel for foot wear comprising a resilient section, a comparatively hard section, and means for holding said sections in place,

each of said sections being substantially wedge shape so that the bottom of the heel 65 will engage the earth flatwise when in use and the top of the heel will incline upwardly toward the rear.

2. A heel for foot wear comprising a base, a removable resilient section arranged at the 70 rear of the base, and a removable front locking section arranged at the front of the base engaging the base and the removable rear section, said rear section acting as spring means for holding the locking section in 75 place.

3. A heel for foot wear comprising a base having a comparatively large front cutout portion merging into a smaller cut out rear portion, said base being provided with an 80 overhanging flange arranged on said cutout rear portion, and an overhanging flange arranged at the front of the front cutout portion, a resilient rear section fitting in said rear cutout portion and formed with a 85 groove for receiving a flange in said rear cutout section, and a locking section formed with a flange at the rear and a groove at the front, said flange engaging the groove in said resilient section and said groove accommodating the flange at the front of said front cutout portion whereby the resilient section and the locking section are both locked in place.

4. A heel of the character described comprising a base having an overhanging flange at the rear and an overhanging flange at the front, a resilient rear section formed with an extension having a groove fitting in said overhanging section at the rear of the base, 100 and a removable locking section having a flange adapted to extend into the groove of said resilient section and a groove at the front for receiving the overhanging section at the front of said base, the resiliency of 105 said resilient section holding the locking section in a locked position.

5. A heel of the character described comprising a base, a removable rubber section at the rear of the base, and a locking section at 110 the front of said base, said rubber section in addition to acting as a wearing member acting as a spring for holding in place the locking section.

6. A heel of the character described comprising a base, a locking section having an interlocking flange interlocking with the base, and a resilient section having an extension provided with a central cutout portion whereby the side of the extension will 115 act as resilient spring means, said extension interlocking with said base and with said locking section and acting on the locking section for holding the flange thereof in engagement with said base.

GEORGE C. SEYMOUR.
